Gas Ryder
Attorney

UNITED STATES PATENT OFFICE.

HERBERT R. GRIFFITHS, OF HOMESTEAD, PENNSYLVANIA.

FURNACE.

Application filed August 5, 1920. Serial No. 401,325.

To all whom it may concern:

Be it known that I, HERBERT R. GRIFFITHS, a citizen of the United States, residing at Homestead, in the county of Allegheny and State of Pennsylvania, have invented certain new and useful Improvements in Furnaces, of which the following is a specification.

This invention relates to furnaces, designed primarily for the production of steel, but it is to be understood that the furnace can be employed for any purposes wherein it is found applicable, and has for its object to provide a furnace, in a manner as herein-after set forth, with a pair of down-take structures, one at each end thereof, and each constructed with a collection chamber having the walls thereof smooth and uninterrupted throughout and further squared off at the lower ends or at the bottom of the chamber, whereby any retardation of the cinder and slag during the down travel thereof through said chamber is prevented, and further to prevent any accumulation of the cinder and slag within the collection chamber, and each of said structures having associated therewith a removable hopper providing a removable bottom for the collection chamber and employed as a pocket for the collection of cinder and slag during the process of combustion, the hopper being so set up that when occasion requires it can be removed and dumped, under such conditions setting up a convenient method for removing the collected cinder and slag.

Further objects of the invention are to provide a furnace for the purpose set forth, in a manner as hereinafter referred to, which is simple in its construction and arrangement, strong, durable, efficient and convenient in its use, readily set up, and comparatively inexpensive to build.

With the foregoing and other objects in view, the invention consists of the novel construction, combination and arrangement of parts as hereinafter set forth and illustrated in the accompanying drawings, wherein is shown an embodiment of the invention, but it is to be understood that changes, variations and modifications, can be resorted to which come within the scope of the claim hereunto appended.

In the drawings wherein like reference

55
ence characters denote corresponding parts throughout the several views:—

Figure 1 is a front elevation of a furnace in accordance with this invention.

Figure 2 is a longitudinal sectional view thereof.

Figure 3 is a section on line III—III 60
Figure 2.

Figure 4 is a section on line III—IV Fig-
ure 3.

A furnace in accordance with this invention includes a central structure and a pair 65 of end structures, the former comprises a base foundation 1, depressed to provide a hearth 2, which has a lining 3, of refractory material, and the said central structure further includes a roof 4, a front wall 5 and 70 a rear wall 6. The front wall 5 has entrance openings or doors 7, so that the material or ore to be acted on, can be supplied to the hearth 2. The rear wall 6 is formed with a discharge port or passage 8. The central 75 structure forms a heating chamber 9, having each end open, as at 10.

Each of the end structures is what may be termed a down-take and as each is similar in construction, but one will be described, as 80 the description of one will apply to the other. The down-takes communicate by flues 25 with the checker-work A.

Each down-take comprises a roof 11, an end wall 12, a rear wall 13, a front wall 85 14, an intermediate partition 15, and an inner end wall 16 which is of less height than the end wall 12.

Each down-take further comprises an inlet chamber 17 and collection chamber 18. 90 The chamber 17 is formed by the upper portion of the outer end wall 12, the roof 11, front and rear walls 13, 14, and the partition 15, the latter forms the bottom of the inlet chamber 17. The open end 10 of the chamber 9 opens into the chamber 17.

The collection chamber 18, is formed by the partition 15, front and rear walls 13, 14 and end walls 12, 16. The wall 16 has the rear portion B thereof tapered towards the 100 checker-work A. One wall of a flue 25 forms a continuation of the taper of the tapering portion B of the wall 16. The tapering of the wall 16 and the wall of the flue 25 allows for greater draft to the checker-work A. 105

The partition 15 forms the roof of the chamber 18, and is provided with an opening 19 whereby communication is established between the chambers 17 and 18.

5 The bottom of the chamber 18, is formed by what may be termed a removable collecting hopper 20, which is provided with a lining of refractory material 21. The hopper 20, which constitutes a pocket, is detachably supported on a shiftable truck 22, which is mounted to travel on a track formed by the rails 23, extended to a position within the down-take below the chamber 18. The rear wall 14, is cut away, as at 24, to provide an

10 opening to allow for the shifting of the truck into and out of the down-take.

Extending into each chamber 17, in proximity to the open end 10, of the chamber 9, is a pair of oppositely disposed burners for 20 gas. The burners for one chamber 17 are indicated at 26 and for the other chamber at 27. When the burners 26 are used the open end 10 in proximity thereto forms an inlet and the other open end 10 of the chamber 9 25 forms an outlet, and the same arrangement relative to the open ends 10, is had when the other burners are used. But one pair of burners is employed at one time.

Associated with each of the trucks 22, is a 30 hydraulic or compressed air cylinder 28, having a piston, not shown, and the latter is formed with a piston rod 29, which is connected with the truck 22, for the purpose of shifting the truck into and out of the down-take when desired. When shifted outwardly the hopper 20 can be removed from the truck, by any suitable elevating mechanism, and then dumped. Eyes 30 are provided on the hopper so the elevating mechanism can be detachably connected therewith. To provide for the sealing of the bottom of 40 each of the chambers 18, the walls 12, 14 and 16 are squared off or under cut at their lower ends to provide shoulders 31, against 45 which the top edges of the sides and inner

end wall of the hopper abuts. The wall 13 is also squared off and cut away to form a bevelled shoulder 32, which extends above the shoulders 31, and against the shoulder 32 abuts the extended upper end of the front 50 end wall of the hopper 20. The front end wall of the hopper is of greater height than the side walls and inner end wall. See Figure 3.

The walls of the chambers 18 are smooth 55 throughout, so that the fall of the cinder and slag will not be interfered with and no accumulation thereof will be had within the chamber 18.

When the burners are ignited the flames 60 pass over the material in the heating chamber and the products of combustion are carried off into the chamber 17, then pass into the chamber 18. The checker-work will be heated from the chamber 18. The cinder 65 and slag will be collected in the hopper and removed when occasion requires.

As the hopper is detachably mounted on the truck, if it becomes damaged it can be readily replaced by a new one without discarding the truck. The hopper is so constructed as to form a complete closure for the bottom of the chamber 18.

What I claim is:—

In combination a furnace having a hearth 75 and a downward passage communicating with the hearth, said downward passage being rectangular in plan and having three of its walls undercut and the other wall bevelled, the bevel extending above the undercuts and said undercut walls providing for the passage of a removable hopper below the passage, said passage adapted to communicate with the checker work of the furnace and having one of its walls tapered inwardly 80 towards the checker work providing the passage of greater width at the checker work 85 whereby the size of the latter is increased.

In testimony whereof I affix my signature.

HERBERT R. GRIFFITHS.
